[57] CLAIM

The ornamental design for siding installation tool, as shown and described.

DESCRIPTION

FIG. 1 is a top, front and left side perspective view of a siding installation tool showing our new design thereof, drawn on a slightly smaller scale;

FIG. 2 is a front elevational view;

FIG. 3 is a right side elevational view;

FIG. 4 is a rear elevational view;

FIG. 5 is a top plan view; and

FIG. 6 is a bottom plan view thereof.

The vertical post of FIGS. 1, 2, 3 and 4 has been shown broken away to indicate indeterminate length.

FIG. 1

FIG. 2

FIG. 3

FIG. 5

FIG. 6

FIG. 4
